United States Patent Office

Des. 229,642
Patented Dec. 25, 1973

229,642

WAFFLE OR THE LIKE

Richard L. Dorsa, 20450 Montalvo Lane,
Saratoga, Calif. 95070

Filed Mar. 31, 1972, Ser. No. 240,338

Term of patent 14 years

Int. Cl. D1—01

U.S. Cl. D1—18

The figure on the drawing is a top view of a waffle showing my new design.

The opposite side of the waffle is of substantially similar appearance and the waffle is of conventional thickness.

I claim:

The ornamental design for a waffle or the like, as shown and described.
